CLAIM

The ornamental design for knife handle, as shown and described.

DESCRIPTION

FIG. 1 is a left side perspective view of a knife handle showing my new design;

FIG. 2 is a left side elevational view thereof;

FIG. 3 is a right side elevational view thereof;

FIG. 4 is a bottom plan view thereof;

FIG. 5 is a top plan view thereof;

FIG. 6 is a front elevational view thereof; and,

FIG. 7 is a rear elevational view thereof.

The broken lines shown in the drawings represent unclaimed portions of the design and environmental structure and form no part of the claimed design.
